COMBINATION BATHTUB AND SHOWER UNIT

Fred C. Alexander, New Castle, Pa., assignor to Universal-Rundle Corporation, New Castle, Pa.

Filed June 23, 1971, Ser. No. 156,168

Term of patent 14 years

Int. Cl. D23—02

U.S. Cl. D23—49

FIG. 1

FIG. 2

FIG. 3

FIG. 4

FIG. 8

FIG. 9

FIG. 11

FIG. 12

FIG. 1 is a front perspective view of a combination bathtub and shower unit showing my new design;

FIG. 2 is a fragmentary front perspective view of a detail thereof, on an enlarged scale;

FIG. 3 is a vertical cross-sectional view thereof taken substantially on line 3—3 of FIG. 1;

FIG. 4 is a vertical cross-sectional view taken thereof substantially on line 4—4 of FIG. 3;

FIG. 5 is a top plan view thereof with the top removed for convenience of illustration;

FIG. 6 is a cross-sectional view thereof taken substantially on line 6—6 of FIG. 1;

FIG. 7 is a cross-sectional view thereof taken substantially on line 7—7 of FIG. 1;

FIG. 8 is a cross-sectional view thereof taken substantially on line 8—8 of FIG. 5;

FIG. 9 is a cross-sectional view thereof taken substantially on line 9—9 of FIG. 5;

FIG. 10 is a fragmentary cross-sectional view of a detail thereof taken substantially on line 10—10 of FIG. 1;

FIG. 11 is a right end elevational view thereof with the top removed; and

FIG. 12 is a left and elevational view thereof with the top removed.

I claim:

The ornamental design for a combination bathtub and shower unit, as shown and described.
